UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed March 14, 1931. Serial No. 452,237.

This invention comprehends improvements of especial utility in the coking retort oven art. The invention has for an object to utilize the gas oven principle in a cross-regenerative coking retort oven having horizontal flame flues in the heating walls, thereby providing a horizontal-flued cross-regenerative oven, in which the heat for coking the charges of coal in the retorts or coking chambers may be developed from the combustion of an extraneously derived special generator gas, such as producer gas, with a resultant conservation of the entire product of the relatively richer coke oven gas derived from the carbonization of the coal charged into the retorts of the oven.

In the accompanying drawings, forming a part of this specification and showing, for purposes of exemplification, a preferred form and manner in which the invention may be embodied and practised, but without limiting the claimed invention to such illustrative instance or instances:

Figure 1 is a crosswise vertical sectional elevation through a coke oven battery embodying the features above specified and equipped with the improvements of the present invention, the view being taken longitudinally through a heating wall and a regenerator, in planes indicated by the line A—A of Figure 2, and

Figure 2 is a composite vertical sectional elevation taken longitudinally of a coke oven battery, in planes indicated by the lines B—B, C—C and D—D of Figure 1.

The same characters of reference designate the same parts in each of the several views of the drawings.

In the embodiment illustrated in the drawings, the invention is incorporated in a combination coke oven battery, i. e., a battery having provision for being operated either with an extraneously derived special generator gas, such as producer gas, or with the coke oven gas derived from the distillation of the coal in the coking chambers of the battery. For convenience, the present description will be confined to the present illustrated embodiment of the invention in such a combination coke oven battery; the novel features

and improvements made by the invention are susceptible of other applications, such, for example, as in ordinary so-called "gas ovens" employing producer gas as the fuel; hence, the scope of the invention is not confined to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11, 11, and a plurality of intermediate crosswise elongated horizontal coking chambers 12, 12. The heating walls 11 form the side walls of the respective coking chambers 12, shown more particularly in Figure 2, and together with the coking chambers are supported by the heavy supporting walls 13, 13, which extend crosswise of the battery and are located, as shown, below the coking chambers and heating walls. The supporting walls 13 collectively form the main support for the entire superstructure of the oven battery and are themselves supported upon a flat mat or platform which constitutes the sub-foundation on which the entire battery rests.

The coal to be coked is charged into the several coking chambers or ovens through charging holes 14 located in the top 15 of the oven battery and positioned, as shown in Figure 2, directly above the ovens or chambers 12. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets indicated by dotted lines at 16 in Figure 1, and thence through ascension pipes (not shown) into the usual gas collecting main, which carries the distillation products to the by-product recovery apparatus.

Heat for coking the charges of coal in the several ovens or chambers 12 is derived from the heating walls 11, which, as above men-

tioned, extend cross-wise of the battery at the sides of the coking chambers. As shown, each heating wall 11 is constituted of a plurality of horizontal flame or combustion flues, 5 17, which extend parallel with the longitudinal axis of the heating wall and are operatively connected in series at the opposite ends of said heating wall, as shown at 18. All 10 of the flame flues of the heating wall, in accordance with the present embodiment of the invention, operate concurrently as burning flues and combustion is maintained concurrently in the flues of half of the heating walls of the battery, while, at the same time, the 15 flues of the other heating walls are operating as outflow flues for the waste gases or products of combustion from the burning flues.

The crosswise regenerators 19 of the retort oven or battery are located below the 20 aforesaid heating walls 11 and coking chambers 12, and in the present instance extend in parallelism between the supporting walls 13.

Each regenerator 19 is a chamber containing open brickwork, commonly called checker-work, and indicated at 20 with a distributing sole channel 21 underneath such checker-work, the channels forming the soles of such chambers and opening up into the checker-work.

20 The regenerators are heated, in alternation, by the hot combustion products that draw off from the flame or combustion flues hereinbefore mentioned, and then impart such heat to the medium that they feed to 25 these flame flues; in the present instance, the regenerators 19 are disposed, taken seriatim longitudinally of the battery, in groups G and H, each said group comprising four regenerators and, as shown in Figure 2, flow 30 is maintained concurrently in the same direction in all the regenerators of each group, but in the opposite direction with respect to the regenerators of the adjacent groups. That is to say, the several groups G of regenerators alternate with the groups H and the flow through the regenerators of the groups G, while in the same direction in all 35 of the regenerators of that group, is in the opposite direction with respect to the flow through the several regenerators of the groups H.

Located at the opposite ends of each heating wall are vertical feed channels 22. The channel 22 at one end of a heating wall is 40 communicably connected, by means of a series of ports 23, with alternate flues of the heating wall, and the feed channel 22 at the other end of the heating wall is communicably connected, by means of a series of ports 24, with 45 the flues that are intermediate the alternate flues aforesaid. During one reversal period, half of the groups of regenerators G and H operate as inflow generators, whereas the other half of such groups of regenerators operate as outflow regenerators. That is to say,

when the several groups G of regenerators are operating for inflow, the several groups H are operating for outflow. Each inflow group of regenerators is composed of two gas regenerators for heating the fuel gas and two air regenerators for heating the air which enters the flues to support combustion of the gas. Assuming that the groups G of regenerators are operating for inflow, each such group comprises two adjacently disposed gas regenerators, P, and two air regenerators, A, respectively located on the opposite sides of the two gas regenerators P. All of the outflow groups H of regenerators operate concurrently as waste gas regenerators and are 50 designated by the reference character W. Each of the gas regenerators P, whether operating for inflow or for outflow, is communicably connected by ports 25 with the feed channels 22 at the opposite ends of an adjacent heating wall, and each air regenerator A, whether operating for inflow or for outflow, is communicably connected, by means of a port 26, with the bottom flame flue of the same heating wall that is connected with the gas regenerator P. The air regenerators A are also communicably connected by ports 27 with the ducts 25 that connect the gas regenerators with the feed channels 22, thereby permitting a portion of the air from the 55 air regenerators to pass into the feed channels 22 along with the fuel gas. With this construction, the flame flues of each heating wall are communicably connected with a pair of adjacent separate regenerators, one of which feeds fuel gas into the flues while the other feeds air, during the period when the flues are operating as burning flues. On reversal, both of the regenerators that are communicably connected with the flame flues of 60 a single heating wall operate concurrently to receive and convey to the stack the waste gases from the outflow operating flues.

The reversal in operation of the flame flues in the several heating walls of the battery takes place longitudinally of the battery, and is effected at the end of an operating period determined by practice, by means of any preferred type of reversing mechanism. The function of such reversal is as follows: The 65 regenerators that, prior to the reversal, operated as inflow regenerators become outflow regenerators, and the outflow operating regenerators become inflow operating regenerators; the burning series of flues switches 70 function with the outflow operating series of flues; and the supply of gas is turned off from the previously burning flues and turned on into the mains of the previously outflow operating flues.

As shown, the top flame flues 17 of two adjacent heating walls are communicably connected by means of a passageway 28, which opens up preferably into the end portions of the respective connected flues 17, as shown 75

in Figure 1. Thus the entire flow from a heating wall, within the flues of which combustion is being maintained, passes into and through all of the flues of the next adjacent heating wall to the outflow operating regenerators that are connected with such flues.

Extending from the opposite side walls of the battery and leading into the feed channels 22 are gas supply channels 29. These gas supply channels register with the ports 23 and 24 at the opposite ends of the flame flues, and are for the purpose of supplying coke oven gas to the several flame flues of each heating wall. The supply of coke oven gas to the respective ports 29 is derived from coke oven gas mains of the usual type and respectively located on the opposite sides of the battery. Suitable means is provided for admitting or cutting off the supply of gas with respect to the channels 29, it being understood that the gas supply may be turned on concurrently in the channels which feed the burning flues and turned off concurrently from those channels which lead to the outflow operating flues.

For operating the battery alternatively with the use of a special generator gas, such as producer gas as a fuel, the several inflow operating regenerators P may be optionally connected with a producer gas main, so that the producer gas may be directed into such of the regenerators as are operating for inflow and conveyed through these regenerators into burning flame flues 17. The operation of the retort oven or battery when using a special generator gas, such as ordinary producer gas as a fuel, is as follows: The supply of coke oven gas to the coke oven gas main, and to all of the coke oven gas channels 29, is cut off. A supply of producer gas is permitted to flow into the inflow operating gas regenerators P, and passing through said regenerators is preheated before being delivered into the burning flame flues. During the inflow of producer gas through such regenerators P, waste gas from the down burning flues is flowing out through all of the regenerators W. In the regenerators A, inflow of air is maintained and, passing upwardly through said regenerators, finally enters the burning flame flues to support the combustion of the producer gas that is delivered thereto by the regenerators P. On reversal of the flow, the inflow gas and air regenerators become outflow regenerators, and concurrently the outflow operating waste gas regenerators become inflow gas and air regenerators.

In operating the battery with coke oven gas, the supply of producer gas to the regenerators P is shut off and air is permitted to flow into such regenerators in place of the producer gas. During coke oven gas operation a supply of coke oven gas is maintained in the channels 29 which feed the burning

flues. The reversing mechanism is operated at each reversal to place all of the inflow operating air regenerators in communication with the outer air, and concurrently all of the outflow operating regenerators in communication with the exhaust.

The invention as hereinabove set forth is embodied in a particular form of construction, but may be variously embodied within the scope of the claims hereinafter made.

I claim:

1. In a coking battery, in combination: heat treating chambers, flued heating walls between successive chambers; regenerators communicating with said flued heating walls respectively adapted to pass preheated air and combustible gas to said flued heating walls and to pass the heated waste gases therefrom, regenerators for passing waste gas being separated from all of the regenerators for passing combustible gas by regenerators for passing air, substantially as specified.

2. In a coking battery, in combination: passages designed to convey respectively air, combustible gas and waste gas, all of the passages for passing the waste gas being separated from all of the passages for passing combustible gas by the passages for passing air, substantially as specified.

3. In a coking battery, in combination: heat treating chamber; flued heating walls between successive chambers; pairs of regenerators for passing respectively preheated air and preheated combustible gas to alternate pairs of said flued heating walls, and for passing the waste gases from intermediate pairs of said walls, two pairs of regenerators for passing the waste gases lying next to each other and being separated from pairs of regenerators for passing combustible gas by a regenerator for passing air, substantially as specified.

4. In the combination defined in claim 3, means for reversing the flow while maintaining the sequence of gases in the several regenerators, substantially as specified.

5. In a coking battery, in combination: heat treating chamber; flued heating walls between successive chambers; groups of regenerators for passing respectively preheated air and preheated combustible gas to alternate groups of said flued heating walls, and for passing the waste gases from intermediate groups of said walls, two groups of regenerators for passing waste gases lying next to each other and being separated from a group of regenerators for passing combustible gas by a regenerator for passing air.

6. The process of operating a coking battery provided with alternate coking chambers and flued heating walls and regenerators communicably connected to said flued walls, which process comprises: passing air to said flued walls through certain of said regen-

erators; passing a combustible gas to said flued walls through other of said regenerators; and removing the hot gases of combustion from said flued walls through still other of said regenerators separated from all of the regenerators passing combustible gas by regenerators passing air.

7. The process of operating a coking battery provided with alternate coking chambers and flued heating walls and preheaters communicably connected to said flued walls, which process comprises: passing air to said flued walls through certain of said preheaters; passing a combustible gas to said flued walls through other of said preheaters; and removing the hot gases of combustion from said flued walls through still other of said preheaters separated from all of the preheaters passing combustible gas by preheaters 20 passing air.

8. The process of operating a coking battery provided with alternate coking chambers and flued heating walls and regenerators communicably connected to said flued walls, which process comprises: passing a combustible gas to alternate pairs of adjacent flued heating walls through adjacent pairs of said regenerators; passing air to the same pairs of heating walls through pairs of regenerators 30 each regenerator of which latter pairs lie on opposite sides of said pairs of adjacent regenerators passing combustible gas; passing the products of combustion from the alternate pairs of walls through the intermediate 35 pairs of walls and thence through pairs of regenerators located on opposite sides of said pairs of air regenerators.

9. The process of operating combustion apparatus which consists in passing currents of 40 a combustible gas to said apparatus; concurrently passing currents of air of combustion for said gas to said apparatus on opposite sides of the currents of combustible gas; burning the air and gas in said apparatus and 45 removing the products of combustion from said apparatus through paths located on opposite sides of said currents of air.
